UNITED STATES PATENT OFFICE

WILLIAM DUBILIER, OF NEW ROCHELLE, NEW YORK, ASSIGNOR TO DUBILIER CON-DENSER CORPORATION, OF NEW YORK, N. Y., A CORPORATION OF DELAWARE

ELECTRICAL CONDENSER

Application filed June 5, 1925. Serial No. 35,259.

This invention relates to electrical condensers, and more particularly to fixed electrical condensers, or condensers of constant capacity in a vacuum.

5 An object of this invention is the production of a condenser in vacuum or rare gas, possessing high efficiency in operation, yet marked simplicity as a whole and in respect to each of its component parts, so that its manufacture is economically facilitated as to both the parts and their assembly.

With these and other objects in view which may be incident to my improvements, the invention consists in the parts and combinations to be hereinafter set forth and recited in the claims, with the understanding that the several necessary elements comprising my invention, may be varied in construction, proportions and arrangement without departing 20 from the spirit and scope of the invention.

In order to make my invention more clearly understood, I have shown in the accompanying drawings means for carrying the same into practical effect, without limiting 25 the improvements in practice to the particular constructions, which for the purpose of explanation, have been made the subject of illustration.

In the drawings forming a part of this 30 specification:

Figure 1 is a view in side elevation, the casing being shown in section;

Fig. 2 is a vertical sectional view taken on line 2—2 of Fig. 1;

35 Fig. 3 is a cross sectional view taken on line 3—3 of Fig. 2;

Fig. 4 is a top plan view, the casing being partly broken away.

Referring by numerals to the drawings, 1 40 represents a casing which is preferably rectangular in general contour. In the top of the casing is a circular opening 2 formed with a flange 3. A cylindrical glass sleeve 4 is mounted upon the flange 3 by means of a slot 5 in the lower end of the sleeve in which the flange 3 is cemented or sealed in any desired manner. The sleeve 4 is formed upon its upper edge with a slot 6 in which is mounted and sealed a hood or cap 7 having a cen-

tral aperture 8, the object of which will hereinafter appear.

Mounted within the casing 1 is a condenser comprising electrically conductive elements or plates 9 and 10 of opposite polarity arranged alternately within a frame. The frame comprises two metallic I-shaped end plates or members 11 and 12 secured together by rods or bolts 13 at the end of each vertical arm of the I plates, and oppositely disposed rods or bolts 14 centrally located between the bolts 13 in said arms. In normal position the plates 11 and 12 are vertical, and all the bolts horizontal.

Transverse horizontal glass, mica or other non-conducting bars or members 15 are mounted upon the bolts 13, and bear against the inner faces of the I plates 11 and 12 at the upper and lower ends of the arms, thus connecting the ends of the arms of the I plates. The condenser plates 9 are mounted upon the bolts 13 and 14 with alternating insulating washers or spacers 16. The plates 9 are fitted snugly on the rods or bolts 13 and 14 to insure perfect contact, and the spacers 16 are of sufficient thickness to admit of interleaving the condenser plates 9 with the condenser plates 10 with sufficient clearance to produce the best results.

The glass, mica or other non-conducting bars 15 mounted upon the rods or bolts 13, are centrally bored to receive rods or bolts 17 which are retained therein by washers or nuts 18 fitted over their respective ends. The bolts 17 of course do not make contact with the casing 1. The condenser plates 10 are mounted upon the bolts 17 alternately with insulating washers or spacers 19. The plates 10, which interleave the plates 9, are fitted snugly on the bolts 17 to insure perfect contact and are connected by an insulated terminal 20. The terminal 20 projects through the opening 3 and an aperture 8 in the hood 7, and is sealed therein, as shown at 21. An outside conductor can be joined to the extremity 22 of the terminal 20.

Air is evacuated from the casing through the sleeve 4, or the casing may be filled with rare gas, or the air may or may not be evacu-

ated, either being within the scope of my invention.

The plates 9 thus extend from side to side in the casing 1, and the plates 10 are vertical between the plates 9, and their opposite lateral edges lie between the upper and lower bolts 13, and between the two bolts 14.

The conductor 20 is connected to the upper bolt 17, which has a snug fit in the apertures through all the plates 10, and thus electrically unites these plates. Also the bolts 13 and 14 similarly unite the plates 9, and the ends of the bolts 13 and 14 and of the members 11 and 12 make contact with the inner surface of the casing 1. Hence the plates 9 can be connected in circuit by being grounded on the casing, as indicated at 23 in Fig. 1.

The unit made up of the members 11 and 12, plates 9 and 10, bars 15, bolts or parts 13, 14 and 17 with washers 16 and 19 may fit the casing 1 snugly, and either rest on the bottom of the casing, or on supports 24 therein, if desired.

The casing can be made in one piece or several pieces united by sealed leak-proof joints, and after the condenser is disposed in the casing, the air can be pumped out through the neck or sleeve 4, and the latter then sealed in the well known way. The casing can be set up with the terminal 20 vertical as shown, or in other positions.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A condenser comprising a casing, a frame in said casing and in contact therewith, electrically conductive elements supported in said frame and in contact therewith, electrically conductive elements cooperating with the first elements and supported in said frame and insulated therefrom, a terminal connected to the last named elements, the casing having an opening through which said terminal projects, an insulating sleeve sealed to the casing around the said terminal, the sleeve being spaced from the terminal and a cap through which said terminal passes sealed to said sleeve.

2. In a condenser frame having I-shaped end members, rods connecting the members, non-conducting bars mounted upon certain of said rods, the bars bearing against the members, armature elements of one polarity mounted upon rods connecting the bars, armature elements of opposite polarity mounted

upon the other rods connecting the end members, and spacers between said elements.

3. In a condenser frame having I-shaped metallic end members, rods connecting the end members by the respective arms of said members, non-conducting end members mounted upon the rods connecting the arms and bearing against the first named end members, rods carried by the non-conducting members, armature elements of one polarity mounted on the first named rods, insulating washers separating said elements, and similar elements of opposite polarity and intervening insulating washers on the rods carrying the non-conducting members.

4. In a condenser, a frame having I-shaped end members, rods connecting the end members, non-conductive end bars mounted upon the rods, rods connecting the bars, armature elements of one polarity mounted upon the rods connecting the end bars, and similar elements of opposite polarity mounted upon the rods connecting the end members and in operative relation with said first-named armature elements.

5. In a condenser, a frame having I-shaped end members, rods connecting said members, non-conductive end bars mounted upon said rods and bearing against said members, armature elements of one polarity mounted upon the rods, and armature elements of opposite polarity in said frame in operative relation with said first-named armature elements.

6. A condenser comprising an evacuated casing, a frame of conductive material within said casing and in contact therewith, armature elements of one polarity supported in said frame and connected thereto, armature elements of opposite polarity supported in said frame and insulated therefrom, a terminal connected to the last-named elements, a casing having an opening through which said terminal projects, an insulating sleeve sealed to the casing around said terminal and spaced therefrom, and a metallic cap through which said terminal passes, the cap being sealed to said insulating sleeve.

In testimony whereof I affix my signature.

WILLIAM DUBILIER.
